UNITED STATES PATENT OFFICE

CHARLES ANDREW COOK, OF MUSKEGON HEIGHTS, MICHIGAN, ASSIGNOR OF TWENTY-EIGHT PER CENT TO GEORGE A. BIGLOW, AND TWENTY PER CENT TO CHARLES G. SMITH, BOTH OF FRUITPORT, MICHIGAN

DESIGN FOR A COMBINED FOLDING TABLE AND SEATS

Application filed November 16, 1931. Serial No. 41,752. Term of patent 7 years.

To all whom it may concern:

Be it known that I, CHARLES A. COOK, a citizen of the United States, residing at the city of Muskegon Heights, in the county of Muskegon and State of Michigan, have invented a new, original, and ornamental Design for Combined Folding Table and Seats, of which the following is a specification, reference being had to the accompanying drawing, forming a part thereof.

The figure is a perspective view of a combined folding table and seats with the table and seats in vertical folded position showing my new design.

I claim:

The ornamental design for a combined folding table and seats, as shown.

CHARLES ANDREW COOK.
